DINNER KNIFE OR THE LIKE

Sam H. Bordelon, Chicago, Ill., assignor to Arthur Salm
Inc., Chicago, Ill., a corporation of Illinois

Application May 5, 1953, Serial No. 24,851

Claims priority, application Germany February 4, 1953

Term of patent 14 years

(Cl. D22—3)

Fig. 1.

Fig. 2.

Fig. 3.

To all whom it may concern:

Be it known that I, Sam H. Bordelon, a citizen of the United States, residing at Chicago, in the county of Cook and State of Illinois, have invented a new, original, and ornamental Design for a Dinner Knife or the like, of which the following is a specification, reference being had to the accompanying drawing, forming part thereof.

In the drawing:

Figure 1 is a top view of a dinner knife showing my new design;

Figure 2 is a side view of the same;

Figure 3 is an enlarged cross-sectional view taken on the line 3-3 of Figure 1.

I claim:

The ornamental design for a dinner knife or the like, as shown.
